No. 11,736

April 13, 1880

UNITED STATES PATENT OFFICE.

JAMES I. HEALEY, OF BROOKLYN, NEW YORK.

DESIGN FOR NEWEL-POST.

SPECIFICATION forming part of Design No. 11,736, dated April 13, 1880.

Application filed March 10, 1880. Term of patent 3½ years.

To all whom it may concern:

Be it known that I, JAMES I. HEALEY, of Brooklyn, in the county of Kings and State of New York, have originated and invented a new and useful Design for Newel-Posts; and I do hereby declare that the following is a full, clear, and exact description thereof, reference being had to the accompanying photograph, forming a part of this specification.

10. This invention has relation to certain improvements in the design of a newel-post consisting of an ornamental base, head, and sides, as illustrated in the accompanying photograph, and which will be hereinafter described in detail of construction, and afterward specifically pointed out in the claims.

The photograph forming a part of this specification represents a perspective view of a newel-post constructed in accordance with my design, the base A thereof consisting of the flat-faced molding *a* and the round-faced or ogee molding *b*, which extend around the four sides of the post. Above the molding *b* are corrugations *c*, or a series of convex surfaces, 25 and joining the upper ends of these corrugated surfaces is a line of rosettes or buttons, *d*. The panels *B* of the post are concave, each of which has a looped wreath, *e*, its ends joining flowers *f*, and within the space formed by the 30 loop of the wreath is an ornament, *g*, and above this ornament is a flower, *h*. The top or head *C* of the post consists of ornamental

scrolls *i*, with rosettes *k*, and a vase, *l*, with heart-shaped ornaments *m*.

Having now fully described my invention, 35 what I claim as new, and desire to secure by Letters Patent, is—

1. A design for the top of a newel-post, consisting of the head *C*, with ornamental scrolls *i*, rosettes *k*, and covered vase *l*, with heart-shaped ornaments *m*, substantially as set forth. 40

2. A design for the sides of a newel-post, consisting of the concave sides *B*, looped wreath *e*, flowers *f*, ornament *g*, within the space formed by the looping of the wreath, and the 45 flowers *h*, substantially as specified.

3. A design for the base of a newel-post, consisting of the flat-faced molding *a*, round-face or ogee molding *b*, corrugations *c*, and rosettes or buttons *d*, substantially as described. 50

4. A design for newel-posts, consisting of the base *A*, with flat-faced molding *a*, round or ogee molding *b*, corrugations *c*, buttons *d*, concave sides *B*, looped wreath *e*, ornament *g*, flowers *f* *h*, and top *C*, having scrolls *i*, rosettes *k*, covered vase *l*, and the heart-shaped ornaments *m*, substantially as set forth. 55

In testimony that I claim the foregoing as my own I affix my signature in presence of two witnesses.

JAMES INGOLS HEALEY.
